US0D1078483S

(12) **United States Design Patent** (10) **Patent No.:** **US D1,078,483 S**
Sager (45) **Date of Patent:** **** Jun. 10, 2025**

(54) **WATER BOTTLE**

(71) Applicant: **Robert David Sager**, Manhattan, KS
 (US)

(72) Inventor: **Robert David Sager**, Manhattan, KS
 (US)

(**) Term: **15 Years**

(21) Appl. No.: **29/819,342**

(22) Filed: **Dec. 14, 2021**

Related U.S. Application Data

(63) Continuation of application No. 29/646,380, filed on May 3, 2018, now Pat. No. Des. 945,274.

(57)

CLAIM

The ornamental design for a water bottle as shown and described.

DESCRIPTION

FIG. 1 is a front elevation view of a water bottle of the new design;

FIG. 2 is a rear elevation view of a water bottle of the new design;

FIG. 3 is a left side elevation view of a water bottle of the new design;

FIG. 4 is a right side elevation view of a water bottle of the new design; and,

FIG. 5 is a top down view of a water bottle of the new design.

The broken lines illustrate environment and form no part of the claimed design.

1 Claim, 5 Drawing Sheets
